Patented Oct. 22, 1963

196,696

RADIANT GAS BURNER

Carl E. Fitzgerald, 8901 Mango Ave., Morton Grove, Ill.

Filed Mar. 8, 1962, Ser. No. 69,138

Term of patent 14 years

(Cl. D81—10)

FIG. 1 is a view in perspective of a radiant gas burner showing my new design;

FIG. 2 is a top plan view;

FIG. 3 is a bottom plan view;

FIG. 4 is a side elevational view, the other side being identical;

FIG. 5 is an end elevational view, the other end being identical.

I claim:

The ornamental design for a radiant gas burner, as shown and described.
